UNITED STATES PATENT OFFICE.

JAMES FRANK DURYEA AND WILLIAM M. REMINGTON, OF SPRINGFIELD,
MASSACHUSETTS.

CLUTCH MECHANISM.

957,602.

Specification of Letters Patent. Patented May 10, 1910.

Application filed July 15, 1907. Serial No. 383,773.

To all whom it may concern:

Be it known that we, JAMES FRANK DURYEA and WILLIAM M. REMINGTON, citizens of the United States of America, residing at Springfield, in the county of Hampden and State of Massachusetts, have invented new and useful Improvements in Clutch Mechanism, of which the following is a specification.

10 This invention relates to clutch mechanisms and is of the type known as "disk-clutches", and the invention relates particularly to a clutch of this type adapted for use in self-propelled vehicles, it being located, as well known, between the engine and the driving axles.

In self-propelled vehicles as at present generally constructed, the engine and clutch are located in a tubular base-part, and it is 20 desirable that the clutch mechanism should be easily removable from said base without rendering it necessary to dismount other parts of the mechanism.

The object of this invention is to provide 25 a clutch construction which, while occupying the same inclosed space as the engine or an extension of said space, may readily be disconnected from the engine on the one side and the driven shaft on the other, and 30 be removed bodily from the base-part or casing, and the invention consists in the construction described in the following specification and clearly pointed out in the claims, the construction in its preferred form being 35 illustrated in the accompanying drawing, in which,—

Figure 1 is a sectional elevation taken in the plane of line 1—1, Fig. 3, showing the mechanism in its unclutched position. Fig. 40 2 is a view similar to Fig. 1 showing the position of the parts when they are in clutch, the plane of this section being on line 2—2, Fig. 3. Fig. 3 is an end elevation of the mechanism shown in the preceding figures, 45 certain parts, however, being shown in section, the plane of which is on line 3—3, Fig. 2. Fig. 4 is a side elevation of the clutch mechanism disconnected from its associated driving and driven parts and partially re- 50 moved from its inclosing casing.

Referring to these drawings, *a* is the end of a driving shaft, as for example the crank-shaft of an engine, and *b* is the end of a shaft to be driven thereby, as the shaft of a

motor vehicle which extends, as these machines are generally constructed, to or is connected with, the driving axle. The clutch mechanism is located between the ends of these shafts, as shown in Figs. 1, 2, and 4, and is inclosed in a suitable casing *c* 55 which, as shown in the drawings, is practically a part of the engine base it being firmly bolted thereto by means of bolts not shown, which extend through the flange or lugs *d* at the left-hand end of the casing, 60 the right-hand end of the casing being connected with the casing of the transmission mechanism to which it is bolted firmly. This is the construction generally followed, 65 that is the engine base, the clutch-casing, 70 and the transmission casing are all firmly secured together or at times, where possible, cast together as one piece, the clutch of course being located between the engine base and the transmission casing. Thus located, 75 and connected on the one side to the engine and on the other side to the transmission mechanism, the removal of the clutch has, as heretofore generally constructed, 80 been a difficult operation and one requiring a very considerable length of time. In the construction forming the subject matter of this application, means are provided whereby the clutch may be bodily removed from the casing *c* through an opening in said casing 85 which is closed by a cap *e* shown separated from the casing in Fig. 4. As seen in Fig. 3, the casing at this point is substantially circular in cross section and the cap *e* constitutes practically one half of 90 this casing circumferentially. When it is in position, it is secured by bolts *f* to a horizontal flange on the casing, along either side thereof, see Fig. 3, and also by other bolts *f* located at the top of the cap. 95

The clutch is supported and connected to the driving and driven shafts *a* and *b* as follows: The end of the engine shaft *a* that extends into the casing *c* is tapered for a portion of its length, and beyond this 100 tapered part is a threaded part *h*. Fitted over the tapered end of this shaft is a disk *k* which has a tight fit thereon and is also secured thereto by a key *m*, if desired (see Fig. 2); a nut *o* is then screwed onto said 105 threaded portion *h* of the shaft to crowd the disk to its seat and also covering the end of the key, and extending beyond the threaded

portion of the cap is a short end p integral therewith and constituting a center bearing for the clutch mechanism.

The clutch frame proper consists of two annular parts,—the outer one of which is indicated by the letter r and the inner one is indicated by s ; the member r , as seen in Fig. 2, is, by means of bolts t , secured to the disk k . The inner member s forms part of the hub member s^1 which is provided with a squared end v which is axially located relative to the circular part, and is adapted to be coupled to the similarly squared end w of the driven shaft b by means of a two-part coupling x . The opposite end of the hub-like member s^1 is recessed to receive the rings y between which balls 3 are located, these elements together constituting a suitable ball-bearing to support this end of the hub s^1 , and with it the annular member s , which is a part thereof, the rings y located in the recessed end of the hub having a tight fit therein, the inner one of these rings having a close fit over the projecting end p of the driving-shaft a . The inner end of the hub s^1 is thus supported in axial alignment with the driving and driven shafts.

When the collar or coupling x is applied to the squared ends v and w it fits in between two shoulders 4,—one on the hub s^1 and the other on the shaft b ,—and in this manner the space 5 is provided between the contiguous ends of these squared portions.

As shown in the drawings, both the inner 35 surface of the rotatable member r and the outer surface of the rotatable member s are provided with oppositely located channels 6 and 7 parallel with the axis of the clutch. This clutch is made up of a series of rings 8 40 having tongues 9 thereon which extend into the channels 7, and other like rings 10 having tongues 12 thereon which extend into the channels 6, these rings being arranged in alternating overlapping relation, one to the other.

In the drawings, the rings 10 are shown as having on each side thereof facing rings 13 of leather or similar material which are riveted to the rings 10, the other rings 8 being of metal. This, however, is a detail of construction which has no reference to the invention and both sets of the rings may be made of metal, if desired. These rings are held in loose contact by means of a circular head 14 on the inner end of the hub s^1 it having a sliding movement thereon toward and from the opposite ends of the hub, as will be described further on.

On the outer end of the circular member s 60 carried by the hub s^1 is a nut 15 screwed onto the member s and constituting an abutment for the clutch rings 8 and 10 when the head 14 is moved toward the abutment. This movement of the head 14 is effected as follows: Mounted on the hub s^1 is a sleeve 16

having on the inner end thereof a flange 17, said sleeve being recessed from the inner end thereof toward the other to receive a stiff spiral spring 18 which bears against the bottom of the recess on the one end and at the other end against the web 19 which extends between the hub and the annular member s and carries the latter, screws 20 passing through the circular head 14 and entering the annular flange 17 on the sleeve to secure the head to the latter, these screws extending through the web 19.

The outer end of the hub s^1 is provided with a ring 21 carrying suitable trunnions 22 which are engaged by a fork 23 clearly shown in Fig. 3, the fork being provided with bearings 24 in the lower half of the casing c in which it may oscillate. The fork 23, by suitable well known connections, may be oscillated by the operator to move 85 the sleeve 16 toward the driving-shaft a pushing the circular head 14 toward the disk k and compressing the spring 18, thus leaving the clutch rings 8 and 10 free to rotate one relative to the other.

In the arrangement shown in the drawings, a being the driving shaft, will rotate the disk k and the circular member r secured to it, and the rings 10, engaging as they do with the grooves or channels 6, will rotate 95 with the member r , the other rings 8 remaining stationary. When, however, the spring 18 is allowed to expand, each of the driving rings 10 will be clamped between two of the driven rings 8, and when this clamping 100 movement is sufficiently strong to prevent the slipping of one set of rings relative to the other, the circular member s and the hub s^1 will rotate as one with the member r , and thus through the coupling x rotate the driven 105 shaft b . If now, it is desired to remove the clutch for the purpose of cleaning or repairing it, the cap e , (as shown in Fig 4 to which reference may now be had) is first removed, then the upper cap of the coupling x is re- 110 moved and the sleeve 16, through the fork 23, moved up to compress the spring 18. This being accomplished, a hole 26, which extends through the squared end v of the hub s^1 is uncovered and into this hole a pin 115 27 is driven which will hold the spring in its compressed position. The bolts t which hold the clutch to the disk k may now be removed and this being accomplished the clutch, as a whole, with the exception of 120 course of the disk k may, after the lower half of the coupling x has been removed, be moved toward the shaft b , the space 5 between the contiguous ends of said shaft and the squared end d of the clutch-hub, having 125 been left for this purpose. This space 5 provides room to slide the bearing ring y off from the centering projection p on the end of the driving-shaft positioning the clutch so that it may be lifted out bodily from the 130

casing, as shown in said Fig. 4. When it is replaced, it is put back in the same manner, the trunnions 22 on the clutch being dropped in their seats in the forks 23, and the clutch 5 then slipped forward over the centering projection p of the driving-shaft, whereupon the bolts t may be replaced and the pin 27 driven part way out, the clutch may be so turned as to allow the lower half of the 10 coupling α to be placed in position, whereupon the pin 27 may be removed entirely, the fork 23 serving to hold the spring 18 in compressed position while the upper half of the coupling α is being bolted in place. It 15 is thus seen that the construction described is such as to greatly facilitate and expedite the removal of the clutch without disturbing other associated parts of the mechanism.

What we claim, is:—

20 1. The combination with a clutch mechanism, of a driving and driven shaft between which said mechanism is located, means to pivotally support said mechanism on one of said shafts, and means including a 25 coupling member α for positively securing said mechanism to the other of said shafts in spaced relation to the end thereof, said mechanism comprising a spring, and means

to secure the spring in a compressed position whereby room is provided to slide the clutch 32 mechanism toward that shaft with which it is in said spaced relation, to disconnect the mechanism from that shaft on which it is pivotally supported.

2. A clutch mechanism having in combination, a driving and a driven-shaft in axial alignment and spaced from each other, a clutch construction located between said shafts and including concentric annular parts, a hub member, a coupling member for 35 securing the hub member to the driven shaft, a sleeve element, a disk member, an expansion spring located between said sleeve and disk, means to compress the spring, and means to retain the spring in a compressed condition, 40 the length of the hub-member being less than the distance between the ends of said shafts, whereby when the coupling member is removed the clutch construction may be bodily removed, as described.
